UNITED STATES PATENT OFFICE.

CHARLES H. AYARS, OF SALEM, NEW JERSEY, ASSIGNOR TO AYARS MACHINE COMPANY, OF SALEM, NEW JERSEY.

CAN-FILLING MACHINE.

Application filed June 11, 1924. Serial No. 719,268.

My invention relates to can filling machines and more particularly to mechanism for automatically shutting off the feed when there is no can in position to be filled. The 5 objects of my invention are to provide simple and efficient mechanism whereby the feed openings are closed except when temporarily cleared by mechanism actuated by a can in its passage to the filling point, and 10 to provide common means for closing and clearing the openings for passage of both granular material and liquid.

These objects, and other advantageous ends which will be described hereinafter, I 15 attain in the following manner, reference being had to the accompanying drawings in which

Figure 1 is a side elevation of part of a can filling machine embodying my invention,

20 Figure 2 a diagrammatic sectional view, partly broken away, on line 2-2 of Figure 1, showing the cut-off in operative position,

Figure 3 a like view showing the cut-off in inoperative position,

25 Figure 4 a sectional view on line 4-4 of Figure 1, and

Figure 5 a fragmentary vertical section showing parts of the granular and brine feeding mechanism.

30 Referring to the drawings, 1 indicates the feed hopper of a can filling machine, 2 the distributing wheel for granular material, 3 the measuring cups for the granular material, 4 the bed plate upon which the measuring wheel rotates which is provided with

35 an opening 5 for passage of granular material and an opening 6 for passage of liquid, 7 the bed plate upon which a liquid measuring wheel 8 rotates, which is provided with an opening 7a adapted

40 to register with opening 6, 9 a liquid cup, 10 a funnel wheel provided with funnels 11 for directing granular material and pockets 12 for directing liquid to cans 13,

45 14 a star wheel, 15 a vertical shaft by which rotation is imparted to the granular measuring wheel, the funnel wheel and the star wheel and 16 guides for directing cans into the machine. The parts above enumerated 50 constitute no part of this invention and the illustration is conventional only.

A rod 17 is rotatably mounted in bearings

upon fixed parts of the frame and has a cut-off plate 18 fixed to its upper end. The cut-off plate is preferably substantially heart shaped and is adapted to be swung over and to close an opening 5 and opening 6 thereby cutting off the feed of both granular material and liquid. A curved arm 19, hereinafter called the actuating arm, has one end 55 pivotally connected at 20 to a fixed part of the frame, adjacent the point of entry of the cans, and normally extends into the path of travel of the cans after they come under the domination of the star wheel. A crank 60 arm 21 is fixed to rod 17 and pivotally connected to a link 22 which is pivotally connected to actuating arm 19 at 23. A coiled spring 24 is connected to crank arm 21 and to a fixed part of the frame and normally 65 holds actuating arm 19 in the path of travel of the cans. Cut-off plate 18 is so positioned upon rod 17 that, when arm 19 is held in the path of travel of the cans, the cut-off plate will be held in the position indicated 70 in Figure 2 and will close an opening 5 and opening 6 thereby shutting off the feed of both granular material and liquid. When a can is fed to the machine and comes under the domination of the star wheel, it contacts 75

the actuating arm 19 and forces it outwardly against the tension of spring 24 and also imparts contra-clockwise movement to rod 17 and retracts cut-off plate 18 to the position indicated in Figure 3 thereby clearing an opening 5 for passage of granular material and opening 6 for passage of liquid. 80

As a can passes beyond the openings and beyond actuating arm 19, the spring automatically restores the cut-off plate to its 85 closed position and the openings remain closed until the succeeding can retracts the cut-off plate.

If for any reason there is a failure in can feed the cut-off plate is held in its operative position with the openings closed until 90 a can is fed and the cut-off plate retracted thereby.

While I have described my invention as taking a particular form, it will be understood that the various parts may be changed without departing from the spirit thereof, and hence I do not limit myself to the precise construction set forth, but consider that 100

I am at liberty to make such changes and alterations as fairly come within the scope of the appended claims.

Having thus described my invention, what I claim as new and desire to secure by Letters Patent is:—

1. In a can filling machine, a distributing wheel having a plurality of measuring cups for granular material; a distributing wheel 10 for liquid material; a bed plate for the granular distributing wheel having openings for discharge of granular and liquid material; a cut-off plate normally closing both openings, and means actuated by the cans 15 for clearing the openings.
2. In a can filling machine, a bed plate; a measuring wheel for granular material mounted thereon; a second bed plate; a liquid measuring wheel mounted thereon, the 20 first named bed plate having an opening for discharge of granular material, and an opening for discharge of liquid, and the second bed plate having an opening for discharge of liquid; a cut-off plate normally closing 25 an opening in the first named bed plate for discharge of granular material and the opening for discharge of liquid, and means actuated by the cans for clearing the openings.
3. In a can filling machine, a bed plate; a 30 measuring wheel for granular material mounted thereon; a second bed plate; a liquid measuring wheel mounted thereon, the first named bed plate having an opening for discharge of granular material, and an opening for discharge of liquid, and the second bed plate having an opening for discharge of liquid; a cut-off plate normally closing an 35 opening in the first named bed plate for discharge of granular material and the open-

ing for discharge of liquid, an actuating arm 40 extending into the pathway of the cans; connections between the actuating arm and the cut-off plate whereby movement of the arm will actuate the cut-off plate to clear the openings, and means normally holding the 45 cut-off plate in closed position.

4. In a can filling machine, a distributing wheel; a bed plate supporting the distributing wheel and having feed openings; means for causing cans to travel through the machine; a pivoted actuating arm extending in the pathway of the cans; a rotatably mounted rod; a cut-off plate carried thereby normally closing the feed openings; a crank arm secured to the rod; a link pivotally secured to the crank arm and the actuating arm, and means for yieldingly holding the actuating arm in the path of travel of the cans and the cut-off plate in closing position. 55

5. In a can filling machine, a distributing 60 wheel; a bed plate supporting the distributing wheel and having feed openings; means for causing cans to travel through the machine; a pivoted actuating arm extending in the pathway of the cans; a rotatably 65 mounted rod; a cut-off plate carried thereby normally closing the feed openings; a crank arm secured to the rod; a link pivotally secured to the crank arm and the actuating arm, and a spring connecting the crank 70 arm with a fixed part of the machine normally holding the pivoted arm in the path of travel of the cans and the cut-off plate in closing position.

In testimony whereof I have signed my 75 name to this specification.

CHARLES H. AYARS.
